UNITED STATES PATENT OFFICE

2,415,256

AIR CONTROL FOR LOCOMOTIVES

Vaughn Mansfield, Memphis, Tenn.

Application July 30, 1945, Serial No. 607,804

13 Claims. (Cl. 110—76)

1
This invention relates to locomotives and, more particularly, to apparatus for providing and maintaining complete and uniform distribution of air in the fire box of a coal-burning locomotive.

In coal-burning locomotives of the type now in use, it has been found that the combustion efficiency averages less than 55 per cent in road service at high burning rates and that the efficiencies of the few best designs range only from 60 per cent to 65 per cent, with the greatest losses resulting from unburned cinders and dry gases. Intensive survey has revealed that combustion inefficiency is directly attributable to improper air distribution and feed through the grate area, and while the many locomotives tested had substantially the same per cent of air opening through the grates, there was a wide difference in the per cent of air flow into the ash pans. Furthermore, repair for such items as arch brick maintenance, cinder cutting, and tube slagging were proportional to the degree of restriction of air flow to the ash pans. These items represent a large per cent of engine maintenance and repair. It is therefore the object of this invention to provide for introduction of sufficient air uniformly distributed into ash pans of locomotives.

A further phenomenon discovered was the gross discrepancy in air flow in different portions of the fire box in a series of measurements taken with an anemometer not only from front to rear, but also from side to side. Another aspect of this invention is the equal distribution of air fed into the ash pan with a resultant equalization of draft through and above the fire.

In accordance with the broader objects of the invention, it is now proposed to provide a series of baffles along an ash pan trough, the baffles being spaced from one another in accordance with the relative furnace volume above the grate section lying inwardly therefrom. Thus it is intended to feed different grate sections in accordance with their different needs, to prevent irregular draft from pulling too much air through small areas, and also to prevent the pulling of air to one part of the fire box from the portion of the ash pan trough which should supply air to another part of the fire box, and to prevent the formation of eddy currents in the air passing into the ash pan.

Another feature of the invention resides in the maintenance of the direction of air entering the ash pan at substantially right-angles to the fore-and-aft dimension of the fire box. This condi-

2
tion previously obtained when a locomotive was standing, but when the locomotive moved forwardly, a rearward component was added to the air flow so that at normal or high speeds, the 5 incoming air was directed to the rear of the fire box in excessive amounts and at undesirably high velocities, and relatively little air entered the front portion of the fire box. As a result, firemen traditionally built up a prodigious and inefficient bank of coal in the rear of the fire box, and even blind rear grate sections have been tried to prevent the rear part of the fire bed from being blown out of the grates. Whereas these former practices treated the symptoms of the disorder and but served to cut down the effective grate area with resultant low combustion efficiencies, it is now proposed to rectify the cause by installing baffles to prevent the rearward flow of air as it enters the ash pan openings. Yet another 10 object is to provide a drop door on the outer side wall of the ash pan trough to facilitate cleaning.

Still another object is to provide a series of 15 baffles extending transversely of the direction of travel of the locomotive, the baffles being spaced from one another in accordance with the volume of the primary combustion region of the fire box lying immediately inward of the baffles so that the 20 spaces between the baffles vary from front to rear to maintain air flow proportional to the furnace volume above each grate section. Furthermore, it is intended that the effective height of the baffles increase from front to rear so that each baffle will catch and deflect the proper 25 amount of air for the space between it and the preceding baffle.

Another object of the invention is to provide, 30 in combination with a series of baffles spaced along the ash pan trough of a locomotive and extending transversely of the fore-and-aft dimension of the trough so that incoming air will be deflected laterally inward into the ash pan, a 35 relatively narrow longitudinal baffle extending immediately below the side edge portions of the grates, with the deflecting surface of the longitudinal baffle spaced from the inner lower edge of the mud ring and disposed at an angle to the horizontal so as to deflect a portion of the laterally moving, incoming air upwardly to the sides 40 of the grates.

These and other objects will be apparent in the following specification and drawings, in which:

Fig. 1 is a diagrammatic side elevation with 45 part of the left-hand side of the locomotive bro-

ken away illustrating typical air distribution from front to rear in a prior art locomotive fire box when the locomotive is in motion;

Fig. 1a is an enlarged, detailed view of the portion of Fig. 1 showing the fire box;

Fig. 2 is a cross-sectional illustration of the average distribution from side to side in a locomotive fire box wherein the air distribution is as shown in Fig. 1;

Fig. 3 is a diagrammatic plan view of the predominant air currents occurring in a prior art locomotive ash pan with the arch removed;

Figs. 4, 4a, 5, and 6 are diagrammatic counterparts, respectively, of the illustrations of Figs. 1, 1a, 2, and 3, but illustrating air distribution in the fire box of a locomotive embodying the invention;

Fig. 7 is a graphic illustration of air pressure patterns of a fire box not utilizing the invention and of a fire box similar in all respects but utilizing the invention;

Fig. 8 is an isometric view of a locomotive ash pan showing the grates, the ash-pan troughs, and the baffles installed;

Fig. 9 is a cross section of the structure illustrated in Fig. 8 but with the grates removed;

Fig. 10 is a fragmentary section showing the baffles and a trough in detail;

Fig. 11 is a view similar to Fig. 10 but showing a modification of the longitudinal baffles; and

Fig. 12 is a fragmentary isometric view similar to the left-hand portion of Fig. 8 but showing baffles increasing in height from front to rear.

Referring now to the drawings, in which like elements are denoted by similar reference numerals, Figs. 1 to 3 inclusive illustrate a prior art locomotive 2 of the Mikado type having the usual flues 3, fire box 4, crown sheet 5, grate 6, grate rods 7, arch 8, arch tubes 9, ash pan 10, and ash pan trough 12. Air is admitted to the ash pan through elongated air inlet openings 14 between the upper side edges of the ash pan 10 and the mud ring 16 at the lower side edges of the fire box 4. For illustrating the problem solved by the invention, it will be assumed that the locomotive is traveling forward at the rate of 60 miles per hour against a head wind of 25 miles per hour so that the resultant air velocity passing the ash pans is 85 miles per hour.

In Figs. 1 and 1a the relative air velocities, averaged from side to side, are indicated by the length of the arrows. It will be apparent that the pressure of the air flowing through the grates and coal bed is low in the region below arch 8, and extremely high in the regions behind the arch, resulting in high burning rates in the rear portion only of the fire box.

Fig. 2 illustrates the side-to-side distribution of the air in the fire box of Figs. 1 and 1a, the vertical arrows indicating relative velocities. Here it will be seen that strong drafts occur at and near the center of the fire box, and that relatively little air flows through the grates and coal near the sides. The reason for these phenomena may be found in Fig. 3 wherein, as shown by the arrows, air sweeps inwardly through the troughs and inlet openings to the rear of the ash pan, and then up through the rear center portions of the grates. It has been found in many instances that instead of getting more air for combustion as the speed of a locomotive increases, at which time more air and more combustion is needed, less total air is obtained. This is because air entering the ash pan troughs blasts backwardly and rearwardly, thereby by-passing the

front portions of the inlets to the ash pans, and also setting up eddy currents in the troughs and inlet openings, particularly at the front. Under some conditions, gases flow downwardly through front portions of the coal bed. It was therefore standard practice for firemen to keep a large bank of coal over the rear grates with a thin bed at the front.

Figs. 4 to 6, inclusive, illustrate the theory of the invention. In an improved engine 20 having the same basic elements as detailed above, series of baffles 22 are spaced in troughs 24 so that air entering openings 14 is distributed evenly as illustrated. For illustrating the invention, the combustion chamber enclosed by fire box 4 is considered as comprising two regions, the first being that in which primary combustion of the coal gases occurs and comprising the space below and behind arch 8, designated 28; the second being that in which secondary combustion occurs and being above and in front of arch 8, designated 30. The volume of region 28 increases from front to rear, and it should be noted that the spaces between baffles 22 also increase from front to rear so that the baffles 22 are spaced from one another substantially in accordance with the volume of the primary combustion region 28 immediately inward thereof.

Fig. 7 illustrates more precisely the achievements of the invention, the base line A denoting the front-to-rear dimension of a locomotive, while dash line 32 represents anemometer readings, averaged from side to side in an unimproved fire box, and taken while the locomotive was standing. At twelve miles per hour, the average reading at the peak rose considerably, while the dips were more pronounced. Full line 34 shows the average readings taken under similar conditions but with baffles installed. Vertical line B represents the side-to-side dimension of a fire box, dotted line 36 representing anemometer readings averaged between front to rear in the unimproved fire box, while full line 38 represents similar readings in the improved fire box.

The structural features of the invention are illustrated in Figs. 8 to 11, in which all elements such as arch, fire box, et cetera not necessary for illustrating the invention have been eliminated, it being understood that the physical embodiment of the invention is applied to a standard locomotive. In these figures it will be seen that a series of baffles 22 is mounted in each ash pan trough 24, the baffles having their flat surfaces parallel to one another and extending transversely of the fore-and-aft dimensions of the troughs. For convenience in cleaning, and as best shown in Fig. 10, each trough is preferably divided into a fixed strip 40 and a hinged section 42, the hinged section being supported by hinges 44 connected to the upper lip 46 of each ash pan 10 and releasably held in normal position by latches which comprise L-shaped strips 49 extending outwardly from fixed strip 40 through openings in hinged section 42 so that the hinged section may be swung open for cleaning out the troughs and pan. When closed, hinged section 42 is retained by pivoted keepers 51 which engage behind the upstanding portions of strips 49. Any of the well-known types of latches, hooks, or the like may be used for this purpose. End walls 50 rigidly affixed to the ash pan close the ends of the troughs, and baffles 22 are welded at 52 to mud ring 16 and at 54 to fixed strip portion 40 of trough 24. While the upper edges of baffles 22 are shown flush with the upper edge of trough

24, they may lie above or below the upper edge of the trough, or may be made to extend successively higher, progressing from front to rear, to accentuate the overlapping effect obtained by the upward and rearward inclination of the trough. This latter arrangement is illustrated in Fig. 12, in which the baffles 22' progressively increase in height from front to rear. In locomotives of the type presently in general use the upward inclination from front to rear of the 10 grate and trough assembly provides a successive overlapping of the baffles if they be mounted with their upper edges substantially flush with the upper trough edges as disclosed in Figs. 8 to 11, inclusive.

As shown in Figs. 8 to 10, an angularly disposed baffle 56 is mounted on the lower side of each mud ring, each baffle being in the form of a flat strip 58 rigidly secured, as by welding, to the bottom of mud ring 16 so as to extend inwardly beneath the side edges of the grates. Strip 58 is cut away, as at 60, to provide air openings, and yet to support the reversely bent portion 62 which deflects a portion of the incoming air to the edges of the grate areas. This type of angle baffle 56 has been found particularly cooperative with baffles 22 since, because of baffles 22, air entering through opening 14 travels substantially laterally inwardly, and not longitudinally of baffles 56, and therefore baffles 56 provide uniform and direct lateral distribution of the air.

Fig. 11 illustrates a modified arrangement for obtaining positive lateral distribution of air. In this figure, all elements are similar to those detailed in Figs. 8 to 10 inclusive, except that, instead of baffles 56, a plurality of strips 57 are welded to the inner edges of baffles 22 so as to direct air to the sides of the grates. It will be noted that baffles 57 are so spaced and angularly disposed as to direct air substantially proportional to the areas between the projections of their planes.

The invention described above is not limited to the specific showing, but is intended to embrace all equivalents within the scope of the following claims.

I claim:

1. In a locomotive having an ash pan and an air inlet on each side thereof elongated in the fore-and-aft direction of the locomotive, a similarly elongated open-top trough shrouding each of said inlets, a series of baffles in each of said troughs, said baffles having their surfaces lying generally transverse to the fore-and-aft direction of said locomotive, whereby to prevent substantial fore-and-aft movement of air in said inlets and to deter the formation of eddy currents in said inlets.

2. In a locomotive having a fire box, an ash pan, and an air inlet on each side of the ash pan elongated in the fore-and-aft direction of the locomotive, a similarly elongated open-top trough shrouding each of said inlets, a series of substantially flat baffles in each of said troughs, said baffles having substantially their entire surfaces lying at right angles to the fore-and-aft direction of the fire box and being spaced from one another.

3. In a locomotive fire box enclosing a combustion chamber, the cross section of which varies in size from front to rear, said fire box having side walls with elongated air inlet openings associated therewith extending in the fore-and-aft direction of the locomotive for feeding

air to the combustion chamber, a longitudinal open-top trough on the exterior of each side of said fire box, said troughs respectively shrouding the openings, the improvement which comprises a series of generally flat baffles having surfaces disposed across the upper portions of each of said troughs, said baffles being longitudinally spaced from one another and having portions extending into said air inlet openings the surfaces of said baffles being disposed transversely to the fore-and-aft direction of the locomotive.

4. The combination claimed in claim 3, the relative spacing between the baffles being proportional to the relative cross section of those portions of the combustion chamber lying inwardly thereof.

5. In a locomotive fire box including a top wall, side walls, a grate comprising a plurality of grate sections disposed across the bottom of said fire box, an ash pan below the grate, an arch defining a primary combustion space between the lower surface thereof and said grate, the arch being spaced from the rear wall of the fire box to provide further primary combustion space to the rear of said arch, said ash pan and said side walls having openings extending longitudinally of the fore-and-aft direction of the locomotive therein for admitting air to said combustion spaces through said ash pan and said grate, and an open-top trough shrouding each of said openings, the improvement which comprises a series of baffles disposed in each of said troughs, the baffles being spaced from one another, the relative spacing between the baffles being substantially directly proportional to the relative volumes of those portions of said combustion spaces respectively lying immediately inward thereof in a direction transversely to the fore-and-aft direction of the locomotive.

6. The combination claimed in claim 5, said baffles having portions extending inwardly of said trough through said openings.

7. The combination claimed in claim 5, said baffles having portions extending inwardly of said troughs through said openings, the surfaces of the outwardly extending portions successively extending above one another progressing from front to rear.

8. In a locomotive fire box including side walls, a grate, and an ash pan below the grate, there being a substantially continuous longitudinal opening extending in the fore-and-aft direction of the locomotive between each of the side edges of the ash pan and the lower side edges of the side walls for admitting air to the ash pan, the improvement which comprises a trough on each side of said ash pan for shrouding the openings, and a series of baffles disposed in each trough, the baffles being spaced from one another and being disposed in vertical planes lying generally transverse to the fore-and-aft dimensions of the locomotive.

9. In a locomotive fire box having side walls, a grate, and an ash pan below the grate, there being a substantially continuous opening extending longitudinally of the fore-and-aft direction of the locomotive between each side of the ash pan and the lower edge of the adjacent side wall, the improvement which comprises an open-top trough on each side of said ash pan shrouding said openings, a series of baffles in each trough, said baffles being spaced from one another along the lengths of said troughs and having surfaces in said troughs disposed substantially transverse to the fore-and-aft dimensions of

the troughs, and air distribution means extending longitudinally of the fire box and having surfaces inclined upwardly and inwardly of the fire box from said openings and having their lower outer edges disposed between the top and bottom of said air openings.

10. In a locomotive fire box including a top wall, side walls, a grate disposed across the lower portion of said fire box, an ash pan below the grate, an arch defining a primary combustion space between the lower surface thereof and said grate, the arch being spaced from the rear wall of the fire box to provide further primary combustion space to the rear of said arch, said side walls having openings associated therewith extending longitudinally of the fore-and-aft direction of the locomotive for admitting air to said combustion spaces through said ash pan and said grate, the improvement which comprises a trough on each side of said ash pan and lying outwardly of said openings, a plurality of upstanding baffles in each of said troughs, said baffles being spaced from one another and having surfaces substantially normal to the fore-and-aft dimensions of the openings and air distribution means extending longitudinally of the fire box and having surfaces inclined upwardly and inwardly of the fire box from said openings and having their lower edges disposed between the top and bottom of said air openings so as to direct one portion of the incoming air stream immediately upward and another portion of said air stream inwardly towards the center of the ash pan.

11. The combination claimed in claim 10, the relative spacing between the baffles being substantially directly proportional to the relative volume of those portions of said primary combustion spaces lying transversely inwardly of said spaces.

12. In a locomotive fire box including a top wall, side walls, a grate disposed across the lower portion of said fire box, an ash pan beneath said grate, and an arch defining a primary combustion

space between the lower surface thereof and said grate, the arch being spaced from the rear wall of the fire box to provide a further primary combustion space to the rear of said arch, said ash pan and said side walls having longitudinally extending openings therebetween for admitting air to said combustion spaces through said ash pan and said grate, the improvement which comprises an L-shaped trough on each side of said ash pan and extending outwardly of said openings, respectively, each of said troughs having a series of upstanding baffles, said baffles being spaced from one another along the length of said trough and respectively extending substantially thereacross, the top edges of each of the baffles forming each series respectively extending higher than the baffle in front thereof, save the first baffle, whereby to expose a surface to rearwardly passing wind substantially unobstructed by the preceding baffle.

13. The combination claimed in claim 10, said air distribution means comprising a plurality of deflector strips supported on the inner ends of said baffles.
